LAMP SOCKET

Laurence Burns, Swampscott, Mass., assignor to
Sylvania Electric Products Inc., Salem, Mass., a
corporation of Massachusetts

Application February 13, 1943, Serial No. 475,831

2 Claims. (Cl. 173—328)

1

This invention relates to supporting devices and has particular reference to sockets for mounting lamps.

An object of this invention is to provide an improved lamp socket.

Another object is to provide an improved socket for elongated fluorescent lamps.

Further objects, advantages and features will be apparent from the following specification taken in conjunction with the accompanying drawing, in which:

Figure 1 is a front elevation of a socket in an illustrative embodiment of this invention;

Figure 2 is an isometric view of the rear of the socket of Figure 1;

Figure 3 is an isometric, vertically centrally sectioned view of the front of the socket of Figure 1;

Figure 4 is a plan view of the socket of Figure 1; and

Figure 5 is an illustration of the use of a pair of such sockets in supporting a fluorescent lamp, with one socket showing a back covering plate such as is used to cover the rear recesses illustrated in Figure 2.

The socket shown and described in illustration of this invention is of the type used as supports and connectors for elongated tubular fluorescent lamps. Such an assembly is shown in Figure 5.

The material of the main body 1 and the back cover plate 2 (Figure 5), is preferably porcelain or other ceramic or suitable electrically insulating material. The electrical connection of the lamp through the socket is made by engaging the contact pins of the lamp base with resilient contact fingers 3 mounted in the socket 1. The base pins are clamped between the fingers 3 and the upright 4 in the socket 1 (see dotted forms 5 in Figure 1). In order to facilitate this clamping action, steps 6 are formed in the fingers 3.

As in Figure 2, the fingers 3 extend downwardly in the socket 1 within recesses formed in the back thereof and are each held in place by the combination of resilient engagement with abutments 7, 8 and 9 and the confining effect of the backing plate 2 overlying the recesses and held to the body 1 by pins 10. The fingers 3 are slightly sprung from their normal set to engage the abutments 7, 8 and 9, and may be removed by removing cover plate 2 and pulling them straight back out of their recesses. Abutments 7 prevent upward movement, abutments 8 prevent downward movement, and abutments 9 press the fingers 3 laterally against a vertical central wall 11, and provide fixed pressure points to aid in providing

firm and uniform resilient resistance to the assembly of the base pins 5 as in Figure 1. Abutments 8 and 9 are provided so that a flush mounting of the back plate 2 may be accomplished.

Electrical connection from the fingers 3 to associated apparatus may be accomplished by securing connecting wires to the connecting screws 12 mounted in the lower portions of the fingers 3, as in Figure 1. Arch openings 13 are formed in the socket 1 to provide an exit for such connecting wires and yet permit a flush and firm mounting of the socket 1 on a support.

The mounting of the socket may be accomplished by inserting a washer in the slot 14 and mounting a bolt downwardly through the washer and in the vertical slot 15.

The upper portion of the socket 1 is formed with a view to supporting the lamp by receiving and holding the base pins 5 thereof and with a view to facilitating insertion and removal of these pins as well as firmly and efficiently holding them in assembled and operative relation with respect to the socket 1.

25 A particular purpose in the formation of the upper portion of the socket 1 is to provide a central guide and divider stud 16 about which the lamp base pins 5 may be completely rotated; in combination with a cross plate 17 to provide a backing and guide for the pins 5; and the support 4 on which the stud 16 is mounted so that the support 4 provides the only support for the stud 16, with the cross plate 17 and the assembly of the support 4, and pin 16, positioned in vertically spaced relation with respect to each other. Support 4, if desired, may in alternate structures, extend from above or either side instead of from below, as shown, as long as it remains the only support for the stud 16, with a clearance in the direction opposite that of the support.

40 As may be seen in Figure 1, a substantially equilateral triangular opening 18 is provided in the front face of socket 1, and when the lamp 19 is mounted by the sockets, as Figure 5, the base pins 5 extend through the opening 18. In order to facilitate assembly and disassembly of the lamp 19 and the sockets 1, a slot 20 is formed in the top of the socket 1, and this slot connects directly with the opening 18 so that the lamp 19 and the sockets 1, may be assembled or disassembled by varying the pins 5 into or out of the opening 18 by way of the slot 20. The stud 16 is located substantially centrally of the opening 18 and directly beneath the slot 20. Thus the 45 stud acts as a guide for the pins 5 as they are in-

serted or removed from, or rotated in, the opening 18.

Directly beneath the stud 16 is a platform 21, and above and to each side of the stud 16 are angled surfaces 22, in alignment with the adjacent angled side of the triangle formation of the opening 18. These surfaces act as cam surfaces against which the pins 5 bear as they are moved in the opening 18, and provide line contacts as an aid in keeping the pins 5 properly aligned.

The topmost front portion of the socket 1 is beveled as at 23 to provide a clearance for the base 24 of the lamp 19 as it is moved in and out of assembled position. If the base 24 strikes the bevel 23, a camming action results which aids in the proper assembly of the lamp.

The backing plate 2, Figure 5, is provided with a strengthening cross-piece portion 25 which is in part made possible by the opening 26 between the crossplate 17 and pin 16. As in Figure 2, the assembly of the pin 16 with the upright 4 is such as to leave a shoulder 27 against which the cross-piece 25 may bear as a support. The plate 2 has an opening into which an abutment 28 extends from the wall 11. This arrangement, in combination with the laterally extending legs 29 of the plate, serves to properly locate and seat the plate 2 in the socket 1.

The entire structure of the body 1 is preferably moulded or otherwise formed as an integral structure, including the stud 16.

What I claim is:

1. A lamp socket of the type used to hold and energize a lamp through contact pins in its base comprising a body portion of insulating material

having a lamp base pin receiving opening in the upper extremity of said body presenting an upwardly opening channel through which said pins enter the opening, a pair of resilient contact fingers extending into said opening acting to establish electric contact with and hold said pins, a stud located centrally in and extending axially of said opening and a tapered supporting arm formed integral with said body, disposed base downward and extending only partially across said opening at the rear thereof to form the sole support for said stud.

2. A lamp socket of the type used to hold and energize a lamp through contact pins in its base comprising a body portion of insulating material having a lamp base pin receiving opening in the upper extremity of said body presenting an upwardly opening channel, through which said pins enter the opening, a pair of resilient contact fingers extending into said opening acting to establish electric contact with and to grip said pins, a stud located centrally in and extending axially of said opening, a tapered supporting arm formed integral with said body, disposed base downward and extending only partially across said opening at the rear thereof to form the sole support for said stud, a platform lying below and parallel to said stud and disposed in the plane of the bottom edge of said opening to form a partial bottom wall thereof and a cross plate extending transversely of the upper portion of said opening at the rear thereof, said plate being located in vertically spaced relation with respect to said stud and its supporting arm.

LAURENCE BURNS.
